UNITED STATES PATENT OFFICE.

MARTIN ERIKSSON, OF DJURSHOLMS-OSBY, SWEDEN.

BRICKWALL AND BUILDING OF SAME.

1,317,782.

Specification of Letters Patent.

Patented Oct. 7, 1919.

Application filed January 4, 1918. Serial No. 210,358.

To all whom it may concern:

Be it known that I, MARTIN ERIKSSON, a subject of the King of Sweden, residing at Djursholms-Osby, Sweden, have invented 5 new and useful Improvements in Brickwalls and Buildings of Same, of which the following is a specification.

The present invention relates to the building by means of bricks of the usual dimensions of stable and heat insulating walls with 10 good bonds and with a less consumption of material than at the usual building of walls.

In the accompanying drawing a wall built according to the present invention is illustrated in a side view in Figure 1, in a vertical section in Fig. 2, in a horizontal section on the line 1—2 of Fig. 2 in Fig. 3, and in a horizontal section on the line 3—4 of Fig. 2 in Fig. 4.

20 According to the invention the wall consists of courses formed by series of two horizontal bricks placed abreast of one another across the wall, and eventually connected by joints of mortar, alternating with other 25 courses formed by three bricks placed on the edge and separated by interspaces *a* of the same or about the same width, which suitably may be unfilled for increasing the heat insulating capacity of the wall, but may also 30 all or some be filled with mortar or beton, if the wall shall support any special load, and for that reason must possess a great solidity, while its heat insulating faculty is of less importance. The bricks in both courses are 35 disposed longitudinally of the wall. The

courses containing two bricks have the outer side edges of the bricks exposed at the faces of the wall and the outer side faces of the outer bricks of the courses containing the three bricks are exposed at the faces of the 40 wall, as clearly shown in Fig. 1 of the drawing.

It is evident that such a wall, especially if the interspaces between the bricks are filled only with air, must obtain a great heat insulating faculty, because the bricks do not run across the whole wall; it is also evident that by this method of building walls good bonds and an essential saving of material are 45 obtained.

Having now particularly described the nature of my invention and the manner of its operation, what I claim is:

A building wall comprising bricks laid 55 horizontally and longitudinally of the wall in alternate courses of twos and threes, the courses containing two bricks being arranged on their sides with their outer side edges exposed at the faces of the wall, and the courses containing three bricks being arranged on their edges to provide two longitudinal voids and to arrange the outer faces 60 of the outer bricks at the faces of the wall.

In testimony whereof I have signed my name to this specification in the presence of 65 two subscribing witnesses.

MARTIN ERIKSSON.
